US00D769865S

(12) **United States Design Patent** (10) **Patent No.:** **US D769,865 S**
(45) **Date of Patent:** **** Oct. 25, 2016**

(54) **PORTABLE ALL-IN-ONE PERSONAL COMPUTER**

(71) Applicant: **Nicholas W. Oakley**, Portland, OR (US)

(72) Inventor: **Nicholas W. Oakley**, Portland, OR (US)

(73) Assignee: **Intel Corporation**, Santa Clara, CA (US)

(**) Term: **14 Years**

(21) Appl. No.: **29/477,890**

(22) Filed: **Dec. 27, 2013**

(51) **LOC (10) Cl.** **14-02**

(52) **U.S. Cl.**

USPC **D14/341**; D14/336

(57) **CLAIM**

The ornamental design for a portable all-in-one personal computer.

DESCRIPTION

FIG. 1 is a front view of a portable all-in-one personal computer;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective bottom view thereof;

FIG. 8 is a front view of the portable all-in-one personal computer from FIG. 1, with the handle in an alternate position;

FIG. 9 is a rear view thereof;

FIG. 10 is a left side view thereof;

FIG. 11 is a right side view thereof;

FIG. 12 is a top view thereof;

FIG. 13 is a perspective bottom view thereof; and,

FIG. 14 is a perspective rear view of thereof, with the stands in an alternate position.

The broken lines shown are included for the purpose of illustrating portions of the portable all-in-one personal computer that form no part of the claimed design.

1 Claim, 14 Drawing Sheets
